UNITED STATES PATENT OFFICE.

ERNEST HICK, OF PITTSFIELD, MASSACHUSETTS.

DESIGN FOR A UNITARY CHAIR AND TABLE.

41,011.

Specification for Design.

Patented Nov. 29, 1910.

Application filed June 25, 1910. Serial No. 568,945. Term of patent 14 years.

To all whom it may concern:

Be it known that I, ERNEST HICK, a citizen of the United States, residing at Pittsfield, in the county of Berkshire and State of Massachusetts, have invented a new, original, and ornamental Design for a Unitary Chair and Table, of which the following is a specification, reference being had to the accompanying drawing, forming part thereof.

Figure 1 is a perspective view, and Fig.

2 a side view, of said combination chair and table, showing my new design.

I claim:

The ornamental design for a unitary chair and table, as shown.

ERNEST HICK.
